Hasegawa

[11] Patent Number: Des. 410,833

[45] Date of Patent: ** Jun. 8, 1999

[54] **MULTI-TOOL**

[76] Inventor: **Katsumi Hasegawa**, 3-9-5
Iwamoto-cho, Chiyoda-ku, Tokyo 101,
Japan

[**] Term: **14 Years**

[21] Appl. No.: **29/073,093**

[22] Filed: **Jun. 30, 1997**

[51] LOC (6) Cl. **08-05**

[52] U.S. Cl. **D8/105; D8/55**

[57] **CLAIM**

The ornamental design for a multi-tool, as shown and
described.

DESCRIPTION

FIG. 1 is an elevation of the front of a multi-tool showing my
new design;

FIG. 2 is an elevation of the back of the multi-tool shown in
FIG. 1;

FIG. 3 is a plan view of the top of the multi-tool shown in
FIG. 1;

FIG. 4 is a plan view of the bottom of the multi-tool shown
in FIG. 1;

FIG. 5 is an elevation of the left side of the multi-tool shown
in FIG. 1;

FIG. 6 is an elevation of the right side of the multi-tool
shown in FIG. 1;

FIG. 7 is a perspective view of the multi-tool shown in FIG.
1, showing the right side, front and bottom of the multi-tool;

FIG. 8 is a perspective view of the multi-tool shown in FIG.
1, showing the right side, back and top of the multi-tool;

FIG. 9 is a perspective view of the multi-tool similar to the
multi-tool shown in FIG. 1, manipulated to an open position,
and therefore showing the multi-tool in an alternative con-
figuration showing the front and bottom of the multi-tool;

FIG. 10 is a perspective view of the multi-tool shown in FIG.
9, showing the back and top of the multi-tool;

FIG. 11 is an elevation of the front of a multi-tool similar to
the multi-tool shown in FIG. 1, shown with elements of the
multi-tool manipulated to open positions, and therefore
showing the multi-tool in as another alternate configuration;

FIG. 12 is an elevation of the back of the multi-tool shown
in FIG. 11;

FIG. 13 is a plan view of the top of the multi-tool shown in
FIG. 11;

FIG. 14 is a plan view of the bottom of the multi-tool shown
in FIG. 11;

FIG. 15 is an elevation of the left side of the multi-tool
shown in FIG. 11;

FIG. 16 is an elevation of the right side of the multi-tool
shown in FIG. 11;

FIG. 17 is a perspective view of the multi-tool shown in FIG.
11, showing the left side, front and top of the multi-tool; and,

FIG. 18 is a perspective view of the multi-tool shown in FIG.
11, showing the right side, back and bottom of the multi-
tool.
